UNITED STATES PATENT OFFICE.

WILLIAM H. SOMMER, OF PEORIA, ILLINOIS.

PULLER FOR WIRE-DRAWING BENCHES.

Application filed February 3, 1927. Serial No. 165,644.

This invention has reference to a puller for a continuous wire drawing bench.

The invention has for its principal object to provide a puller arranged for quick attachment to and detachment from the successive drums of a continuous wire drawing bench, to facilitate the threading of the wire, to be drawn, through the successive dies and the wrapping of such wire around the several drums.

The invention comprehends a puller arranged for quick slip on and off connection with the flange of the drums of a continuous wire drawing bench, and adapted when tension is applied to frictionally engage upon such flanges, thereby enabling rotative movement to be applied through the puller to the drum or drums.

That the invention may be more fully understood, reference is had to the accompanying drawings forming part of this description, illustrating a preferred embodiment of the invention, in which:

Fig. 1 is a partial plan, more or less diagrammatic, showing a continuous wire drawing bench and my puller applied to the flange of one of the drums;

Fig. 2 is a front elevation of what is shown in Fig. 1;

Fig. 3 is a detail showing the puller applied to the flange of a drum;

Fig. 4 is a detail in section of what is shown in Fig. 3;

Fig. 5 is a cross-section of a clamp to grip the wire; and

Fig. 6 is a sectional detail, as the same would appear on the line 6—6, Fig. 5.

Like characters of reference denote corresponding parts throughout the figures.

The drawing bench shown is for illustrative purposes only, and except in so far as the flanged drums are employed, forms no part of the present invention. This bench is designated A and includes two or more wire drums *a* having flanges *a'*; drawing dies *b*; wire guiding rollers *c*, and the block *d*, together with the necessary and usual operating parts.

Preliminary to threading the machine with the wire to be drawn; the wire, which for convenience is designated B, is preferably pointed as at *c*, *c'* and *c''*, see Fig. 5, in some suitable pointer, not shown, to facilitate such wire being threaded through the

successively smaller dies on the bench, and as it is threaded through each die, a clamp is caused to grip the end of the wire and the puller applied to the flange *a'* of a drum *a* and the drums rotated several turns to warp or coil the wire therearound, while between each drum the wire is passed over or around the guiding rollers *c*. While I have shown the wire B pointed with several successive reductions, this method of pointing need not be followed and only a single or tapered point provided thereon.

The puller comprises a yoke 1 with ends 2 and 3 of preferably unequal length, so that as the yoke is caused to embrace a flange *a'* of a drum *a* the end 2 will lie on the inner side of the flange *a'* and the end 3 will lie on the outer side of the flange *a'*, see Fig. 4. Then when tension is applied to the puller so as to cant the yoke on the flange of the drum, as shown in Fig. 3, a frictional grip is set up between the puller and the drum, permitting the puller to be employed as a crank for manually manipulating or turning the drum to wrap or coil the wire therearound. Release of the tension allows the puller to be released and easily removed or dropped from the drum. Thus the puller is arranged for quick slip on and off connection with the flange of the several drums. Connected to and extending laterally from the end of the yoke 1 is a handle or hand-grip 4, and connected to and extending laterally from the end 2 of the yoke 1 is an ear or lip to which is connected one end of a flexible member 6, the other end of which is connected to a clamp 7. This clamp includes the preferably tubular and conical shaped head 8 in which are located the separable jaws 9 backed by a washer 10 and a coil spring 11 against which the washer bears and one end of which is secured in the head 8. The pointed end of the wire may be easily slipped through the head 8 of the clamp and between the jaws 9, then when pull is applied the jaws firmly grip the wire.

What I claim is:

1. A puller for use in connection with wire drawing benches, comprising a member having a yoke portion arranged for quick slip on and off connection with the flange of a drum and adapted when canted to frictionally engage such flange, means to connect a wire with said member, and a hand-hold

to permit manual operation of said member.
2. A puller for use in connection with wire drawing benches, comprising a member having a yoke portion arranged for quick slip on and off connection with the flange of a drum and adapted when canted to frictionally engage with the sides of such flanges, whereby through manual manipulation of said member said drum may be rotated, a hand-hold extending laterally from

one side of said yoke and a flexible member connected to the other side of said yoke.

3. A puller for use in connection with wire drawing benches, comprising a yoke member having unequal sides, a hand-hold connected to and extending laterally from the longer side of said yoke and a connection for a flexible member extending laterally from the shorter side of said yoke. 15

WILLIAM H. SOMMER.
